Attorneys,

UNITED STATES PATENT OFFICE.

JOSEPH A. DISCHINGER, OF TONAWANDA, NEW YORK.

SUPPORT FOR HANKS OF SILK, YARN, AND THE LIKE IN TREATING-MACHINES.

1,384,052.

Specification of Letters Patent. Patented July 12, 1921.

Application filed April 22, 1920. Serial No. 375,874.

To all whom it may concern:

Be it known that I, JOSEPH A. DISCHINGER, a citizen of the United States, residing at Tonawanda, in the county of Erie and 5 State of New York, have invented new and useful Improvements in Supports for Hanks of Silk, Yarn, and the like in Treating-Machines, of which the following is a specification.

10 This invention relates to an arm for supporting hanks of silk, yarn and the like in machines for de-gumming or otherwise treating material in a tank containing hot soapy water.

15 Arms for this purpose as heretofore constructed have been unsatisfactory on account of their structural weakness which soon causes them to become inoperative by reason of breakage or bending out of their 20 proper shape by the weight of the hanks of wet silk, while the latter are suspended over the tank.

It is the purpose of this invention to provide an arm for this purpose which is strong 25 and durable and permits of properly supporting the hanks of silk or the like without interfering with the latter and without liability of breaking under the load which is normally imposed on the same.

30 In the accompanying drawings: Figure 1 is a fragmentary top plan view of a de-gumming machine provided with hank supporting arms embodying my improvements. Fig. 2 is a vertical longitudinal section of 35 the same. Fig. 3 is a cross section, on an enlarged scale, of one of the arms taken on line 3—3, Fig. 2. Fig. 4 is a fragmentary longitudinal section taken on line 4—4, Fig. 3.

40 Similar characters of reference indicate corresponding parts throughout the several views.

10 represents the tank of the de-gumming machine which is preferably constructed of 45 metal and adapted to hold a bath of hot soapy water or other liquid for treating hanks of silk or other material of this general character.

Extending transversely across the top of 50 this tank are a plurality of arms for supporting the hanks to be treated in the liquid in the tank which arms in the preferred embodiment of my invention are each constructed as follows:

55 11 represents a horizontal supporting arbor or axle which is preferably made hollow

and of metal and provided in its opposite ends with reinforcing bushings 12 which are preferably secured therein by brazing. The inner end of this arbor is removably journaled in a bearing 13 arranged on the side of one wall of the tank while the other end of the same projects beyond the other wall and is secured by a pin 14 upon a rotatable spindle 15. Both ends of the supporting 60 arbor and the bushings thereof are perforated to permit of attaching either one of these ends to the spindle by the pin 14. The spindle is journaled at its outer end in a yoke 16 which in turn is capable of swinging vertically on an operating or adjusting shaft 17 which is arranged lengthwise adjacent to the outer side of the tank and journaled in bearings 18 thereon. This operating shaft is turned from time to time by 70 a hand wheel 40, and this intermittent movement is transmitted to each of the spindles and the parts connected therewith by a worm 19 arranged on the operating shaft and meshing with a worm wheel 20 on the 75 spindle.

Adjacent to its opposite ends each of the supporting arbors is provided with circular supporting heads 21 of metal which are preferably brazed to the arbor and each provided in its marginal part with an annular 80 row of openings 22.

23 represents a plurality of supporting rods, preferably of tubular form, arranged in an annular row around the arbor and each 90 secured at its opposite ends in a pair of openings 22 in the heads. The latter are strengthened by means of reinforcing collars each of which is preferably constructed of metal in the form of a cup and secured with its 95 web 26 to the arbor while its circular flange 27 is secured to the outer side of one of the heads by brazing or otherwise.

Intermediate of the heads the supporting rods are further sustained by a plurality of 100 supporting disks each of which is constructed of metal in the form of a cup and secured with its web 24 by brazing to the arbor while its peripheral cylindrical flange 25 is provided with a plurality of notches 105 28 which are arranged in an annular row and form seats. Each of the supporting rods is secured with its inner side in corresponding notches of the several disks by brazing, so that the outer side thereof projects radially outward beyond the periphery 110 of these disks. Single disks are preferably

arranged on the arbor adjacent to the inner sides of the heads and connected with the latter at their flanges but those disks on the intermediate part of the arbor may be arranged in pairs, as shown in Figs. 1, 2 and 4, in which case the members of each pair of disks have the edges of their flanges abutting each other and brazed together.

A supporting arm of this construction is very strong and capable of properly supporting the hanks of silk or yarn which are hung on the same without danger of breakage or derangement and without being unduly heavy and difficult to operate. Furthermore, this form of arm presents no sharp or rough corners against which the hank of silk is liable to be caught and interfere with the treatment of the same.

In practice a tubular covering or stocking 29 of textile material is drawn over the several rods and disks so as to prevent direct contact of the hanks with the arm when the same are hung thereon.

The several members of the supporting arm may be constructed of any suitable metal which will not rust and stain the silk, such for instance as aluminum, but it has been found satisfactory in practice to construct these members of iron and steel and electroplate the same with nickel in order to prevent rusting and staining of the silk.

During the normal operation of the machine the arms are arranged horizontally and the same are rotated either slowly or intermittently so that the hanks or skeins of silk hanging thereon will be shifted like a belt and all parts are caused to be acted upon uniformly by the treating solution in the tank. The finished hanks may be removed from the arms and replaced by others to be treated upon raising the free ends of the arms clear of their bearings, this being possible by reason of the rotatable connection between the yokes and the operating shaft.

This construction of supporting arm is not only very light but owing to the trussing effect produced by the manner of connecting the several parts, a very strong and stiff arm is obtained which will reliably support and not give way under the weight of the material which is hung on the same for treatment.

I claim as my invention:

1. A machine for treating hanks of silk and the like having an arm for supporting said hanks which comprises an arbor, a plurality of disks mounted in spaced relation on said arbor and each having a plurality of notches arranged in an annular row in the periphery of the disk, and a plurality of longitudinal rods arranged in an annular row around the arbor and each secured with its inner side in corresponding notches in said disks in such position that the outer side of the same is arranged radially out-

ward beyond the periphery of the several disks.

2. A machine for treating hanks of silk and the like having an arm for supporting said hanks which comprises an arbor, a plurality of disks arranged in a longitudinal row on said arbor and each having a radial web and a cylindrical flange arranged on the outer edge of said web and provided with an annular row of notches forming 75 seats, and a plurality of longitudinal rods arranged in an annular row around said arbor and each secured with its inner side in corresponding notches of the several disks while the outer side thereof projects 80 radially outward beyond said flanges.

3. A machine for treating hanks of silk and the like having an arm for supporting said hanks which comprises an arbor, a plurality of disks arranged in a longitudinal 85 row on said arbor and each having a radial web and a cylindrical flange arranged on the outer edge of said web and provided with an annular row of notches forming seats, and a plurality of longitudinal rods arranged in 90 an annular row around said arbor and each secured with its inner side in corresponding notches of the several disks while the outer side thereof projects radially outward beyond said flanges, some of said disks being 95 arranged in pairs and the members of each pair having their flanges abutting each other at their edges.

4. A machine for treating hanks of silk and the like having an arm for supporting 100 said hanks which comprises an arbor, a plurality of circular heads secured to said arbor adjacent to opposite ends thereof and each having an annular row of openings, a plurality of disks secured at intervals to the intermediate part of said arbor and each provided on its periphery with an annular row of notches, and a plurality of rods arranged in an annular row around said arbor and each engaging its opposite ends in corresponding openings in said heads while its intermediate part has its inner side secured in said notches and its outer side projecting 110 radially outward beyond the periphery of said disks.

5. A machine for treating hanks of silk and the like having an arm for supporting said hanks which comprises an arbor, a plurality of circular heads secured to said arbor adjacent to opposite ends thereof and each having an annular row of openings, a plurality of disks secured at intervals to the intermediate part of said arbor and each provided on its periphery with an annular row of notches, a plurality of rods arranged 120 in an annular row around said arbor and each engaging its opposite ends in corresponding openings in said heads while its intermediate part has its inner side secured 125 in said notches and its outer side projecting 130

radially outward beyond the periphery of said disks, and cup-shaped collars secured with their webs to said arbor adjacent to the outer side of said heads while their flanges are connected with the outer side of said heads.

6. A machine for treating hanks of silk and the like having an arm for supporting said hanks which comprises an arbor, a plurality of circular heads secured to said arbor adjacent to opposite ends thereof and each having an annular row of openings, a plurality of disks secured at intervals to the in-

termediate part of said arbor and each provided on its periphery with an annular row 15 of notches, and a plurality of rods arranged in an annular row around said arbor and each engaging its opposite ends in corresponding openings in said heads while its intermediate part has its inner side secured 20 in said notches and its outer side projecting radially outward beyond the periphery of said disks, said arbor being hollow and provided in its ends with reinforcing bushings.

JOSEPH A. DISCHINGER.
